Primary Examiner — Sandra Snapp*Assistant Examiner* — Mehri Bajoul(74) *Attorney, Agent, or Firm* — Woodard, Emhardt, Henry, Reeves & Wagner, LLP(57) **CLAIM**

The ornamental design for a collapsible hockey table, as shown and described.

DESCRIPTION

FIG. 1 is a perspective view of a collapsible hockey table. FIG. 2 is a side view of the collapsible hockey table with the opposite side being a mirror image.

FIG. 3 is an end view of the collapsible hockey table with the opposite side being a mirror image.

FIG. 4 is a top view of the collapsible hockey table.

FIG. 5 is a bottom view of the collapsible hockey table.

FIG. 6 is an exploded view of the collapsible hockey table with the legs in an expanded configuration; and,

FIG. 7 is an exploded view of the collapsible hockey table with the legs in a collapsed configuration.

The broken lines are included for the purpose of illustrating portions of the collapsible hockey table, and form no part of the claimed design.
